COMBINED FLOOR BRUSH AND DUSTER

James M. Oberti, San Francisco, Calif.

Application May 11, 1933, Serial No. 670,574

10 Claims. (Cl. 15—231)

My invention relates to improvements in combined floor brush and duster, and it consists of the combinations, constructions and arrangements hereinafter described and claimed.

An object of my invention is to provide a combined floor brush and duster, which is an improvement over my copending application Serial No. 634,042, filed September 20, 1932.

In the copending application I show a floor duster in which the handle has a universal connection with the cleaning member so that a rotation of the handle about its longitudinal axis will swing the cleaning element into the various angular positions on the floor. I further show spring-actuated clips for holding rolls of dusting cloth on top of the cleaning member. I find it inconvenient to secure the rolls of cloth to the clips after a clean section of cloth has been substituted for a soiled section.

To overcome this disadvantage I provide in the present case spring-actuated clips which are designed to move away from each other in the same manner as a pair of jaws, and this movement will free the rolls of cloth from the cleaning member. After a clean section has been brought into position, the spring clips can be freed and will return to normal position, and this movement will cause the rolls of cloth to ride upon the cleaning member, without any further aid from the operator.

A further object of my invention is to provide a clip which can automatically accommodate itself to rolls of various thicknesses. The clip is also designed to be self-locking and in this way the accidental freeing of the cloth-engaging members is prevented.

Other objects and advantages will appear in the following specification, and the novel features of the device will be particularly pointed out in the appended claims.

My invention is illustrated in the accompanying drawings forming a part of this application, in which

Figure 1 is a front elevation of the device showing the novel types of clips;

Figure 2 is a top plan view showing the dusting cloth in position;

Figure 3 is an enlarged top plan view of one of the clips;

Figure 4 is a side elevation of Figure 3;

Figure 5 is a section along the line 5—5 of Figure 3 showing the clip raised into released position;

Figure 6 is a section along the line 6—6 of

Figure 4 showing the cloth engaging members moved into releasing position.

Figure 7 is an enlarged end view of the device shown in Figure 2.

In carrying out my invention I provide a cleaning member of the same construction as shown in my copending application above referred to. The member comprises a metal frame 1 having a piece of flexible material such as rubber 2 secured between the upper and lower parts of the frame 1. The rubber extends beyond the marginal edges of the frame 1, and in this way acts as a shock absorber, and also prevents the frame 1 from marring the furniture, and other objects contacted by the cleaning member. The frame 1 causes the opposite edges 3 of the rubber piece 2 to be inclined downwardly at a slight angle, and this construction spaces the lower metal piece above the floor 4. In this way the rubber piece 2 protects the metal pieces 1 from contacting with any object.

A handle 5 has a universal connection with the cleaning member, and this is accomplished by means of a pin 6 which pivotally secures the handle to a connecting member 7. The connecting member in turn is pivotally secured at 8 to the cleaning member 1, and the pivot 8 extends at right angles to the pivot 6. In this way a simple universal connection is afforded between the handle 5 and the cleaning member. The cleaning member is broad enough in area to prevent it from over-turning and this permits the handle 5 to be rocked along its longitudinal axis for swinging the cleaning member into various angular positions with respect to the floor 4. This feature has been clearly set forth in my copending application.

I employ two clips indicated generally at A and B, for removably securing rolls 9 and 10 of a dust-absorbing material, such as dusting cloth 11 to the member 1. The dusting cloth 11 is in the form of a single strip of material, and the ends of the cloth are wrapped around the rolls 9 and 10. The cloth is wider than the length of the cleaning member 1, and it is also passed around the edges 3 of the resilient member 2, and the rolls 9 and 10 carrying the unused portions of the cloth are mounted on top of the member 1. When the section of cloth disposed below the member becomes soiled the rolls 9 and 10 are freed from the member 1 by actuating the clips A and B in the manner hereinafter described, and then the soiled section is wound upon one of the rollers, and a clean section is unwound from the other roller. The cleaning member 1 is now

placed over the clean section of cloth, and then the clips A and B are released and will cause the rolls 9 and 10 to move up on the cleaning member 1, and to be securely held in place until the operator again wishes to free the rolls.

Since both of the clips A and B are identical to each other, a description of one will suffice. The clip A is shown in detail in Figures 3 to 6 inclusive. A strap 12 is permanently secured to the frame 1 by means of bolts 13 or other suitable fastening means. The portion 14 of the strap 12, see Figure 4, disposed between the bolts 13, is raised above the metal piece 1 and provides a space 15 for slidably receiving a guide.

The guide 16 is of the shape shown in Figures 4, 5, and 6, and comprises a body member 17 that is slidably mounted between the metal frame 1 and the raised portion 14 of the strap 12. The body 17 has ears 18 which extend upwardly and are mounted on either side of the strap 12, see Figure 6. The ears are spaced from the sides of the strap 12 for a purpose hereinafter described.

The guide 16 also has a slot 19 for slidably receiving the strap 12 and the end of the guide disposed opposite the ears 18 is bent back upon itself as shown at 20 for providing a guide for roller-engaging arms or members 21 and 22. The members 21 and 22 are of the shape shown in Figure 4, and these members are pivoted at 23 and 24 to a bracket 25, which in turn is pivoted at 26 to the strap 12. Openings 27 and 28 are provided in the guide 16 and it will be noted that they are arranged so as to slidably receive the roller-engaging members 21 and 22. The edges 29 and 30 of the openings are utilized for swinging the members 21 and 22 into closed position, while the edges 31 and 32 are utilized for moving the members into opened position. The openings 27 and 28 are designed so as to not create a binding action on the members 21 and 22 at any time.

The means for moving the guide 16 comprises a lever 33, see Figure 4, pivoted at 34 to a bracket 35, which in turn is secured to the strap 12 by means of the pin 26. A link 36 pivotally connects the lever 33 with the ears 18 of the guide 16, and it will therefore be seen that a movement of the lever from the position shown in Figure 4 into that shown in Figure 5 will move the guide 16 to the right. The movement of the guide is indicated between the full line position in Figure 6 and the dotted line position C shown in the same figure. This movement will cause the edges 31 and 32 of the openings 27 and 28 to swing the members 21 and 22 outwardly about pivots 23 and 24. A torsional spring 37 is mounted on the pivot pin 34, and has its ends engaging with the bracket 35, and the pivot pin 38 of the link 36 for causing the lever 33 to swing back into closed position when the lever is freed. It will be noted from Figure 4 that when the lever 33 is in closed position the pivot pin 38 is swung slightly beyond dead center position, and in this way the device is self-locking. The free ends of the roller-engaging arms 21 and 22 extend below the top of the frame 1, see Figures 1 and 7. Figures 4 and 5 show details of the clips and ends of the arms 21 and 22 are shown cut off at the top of the frame 1 although actually they extend below as shown in Figures 1 and 7.

Referring to Figure 1 it will be seen that a cord 39 has a knob 40 secured to its upper end, and the cord is passed through an eyelet 41 mounted in the handle 5. Cord sections 42 and 43 branch off from the cord 39, and these sections are secured to rings 44 carried by the free ends

of the levers 33 of the clips A and B. When the knob 40 is raised it will pull upward the cord sections 42 and 43, and this in turn will swing the levers 33 of both clips A and B into released position. This movement as already described will swing the roller-engaging members 21 and 22 into the position shown in Figure 6. This is sufficient to free the rollers from the member 1, and to permit a new section of cloth to be brought into place. The members 21 and 22 are swung into a wide enough angle to entirely free the rollers from the frame 1. After the change of cloth has been made the mere freeing of the clips A and B will cause the members 21 and 22 to swing toward each other, and this will carry the rollers 9 and 10 up on top of the frame 1. The ends of the arms 21 and 22 are disposed close enough to the floor 4 as shown in Figures 1 and 7, to engage with the rollers 9 and 10 when the latter are resting on the floor and when the arms are in extended position as shown in Figure 6. A mere swinging of the arms into the full line position shown in Figure 3 will move the rollers in the manner stated.

In order to accommodate rolls of different thicknesses, I provide a space between the ears 18 and the strap 12, and I also provide an elongated slot 19 which is longer than the width of the strap, see Figure 6. If, for example, the roll 10 has more cloth on it than the roll 9, the movement of the members 21 and 22 back into closed position will cause the member 21 of the clip A to first engage with the roll 10. The spring 37 is strong enough to keep the members 21 and 22 moving toward each other until both members engage with the rolls of cloth 9 and 10. The guide 16 is free to shift laterally with respect to the strap 12, and this movement is clearly shown in Figure 3. It will be noted from this figure that the guide 16 has shifted to the dotted line position shown at D, and this will cause the link 36 and the lever 33, together with the bracket 25, to swing about the bolt 26 as a pivot. This will permit the member 21 to assume the dotted line position shown at E, and the member 22 to assume the dotted line position shown at F. It will be seen from this construction that the clamping action of the clip is not interfered with in the slightest, and that the clip can automatically accommodate itself to rolls of different thickness.

The distance between the free ends of the members 21 and 22, when they are in closed position, will remain substantially constant, and this is sufficient to create a gripping effect upon the rollers 9 and 10 at all times regardless of the amount of cloth wound on either roller. Figure 3 shows the shifting of the guide 16, members 21 and 22, in a clockwise direction from the full line position. The device is adapted to shift to the same extent in a counter-clockwise direction from the same full line position.

A greater leverage is afforded with this type of clip than the type shown in my copending application. In my copending device the entire force was exerted by the spring 19. In the present device the force is exerted by the spring 37 and the operative connection between the lever 33, and the members 21 and 22 is such as to build up this force so that a relatively great clamping action is exerted upon the rollers 9 and 10 by the members 21 and 22. When the members 21 and 22 are in closed position they are disposed adjacent to the edges of the frame 1, as clearly shown in Figure 3. This prevents the rollers from dropping off the frame.

While I have shown only the preferred form of my invention, it should be understood that various changes or modifications may be made within the scope of the appended claims without departing from the spirit of the invention.

I claim:

1. In combination, a guide strap, a guide movable therealong and also having freedom of a slight lateral movement with respect to the strap, 10 said guide having laterally spaced slots therein, a bracket pivoted to the strap for movement laterally of the strap and guide, arms pivoted to the bracket for movement laterally of the strap and guide and being slidably received in the slots, a 15 second bracket pivoted to the strap on the same pivot that supports the first bracket, a lever pivoted to the latter bracket, a link connecting the lever with the guide, whereby a swinging of the lever will swing the arms, said guide, arms 20 and first and second brackets being swingable a slight distance about the common pivot point of the first and second brackets.

2. In a cleaning device, a flat, rectangular frame having downwardly inclined side edges, a 25 cloth disposed underneath the frame, two rollers having the ends of the cloth wound thereon and adapted for movement from positions alongside opposite sides of the frame up the inclined side edges to positions on top of the frame and 30 means mounted upon the frame for effecting such movement.

3. In a cleaning device, a flat, rectangular frame having downwardly inclined side edges, a cloth disposed underneath the frame, two rollers 35 having the ends of the cloth wound thereon and adapted for movement from positions alongside opposite sides of the frame up the inclined side edges to positions on top of the frame and 40 means mounted upon the frame for effecting such movement, the latter means being shaped to engage the rollers from opposite sides for holding the same in position on top of the frame.

4. In a cleaning device, a flat, rectangular frame having downwardly inclined side edges, 45 a cloth disposed underneath the frame, two rollers having the ends of the cloth wound thereon and adapted for movement from positions alongside opposite sides of the frame up the inclined side edges to positions on top of the frame and 50 means mounted upon the frame for effecting such movement, the latter means being shaped to engage the rollers from opposite sides for holding the same in position on top of the frame, and having means for freeing the rollers from said 55 first named means for permitting the rollers to move in the opposite direction down the inclined side edges.

5. In a cleaning device, a flat, rectangular frame having downwardly inclined side edges, a 60 cloth disposed underneath the frame, two rollers having the ends of the cloth wound thereon and adapted for movement from positions alongside opposite sides of the frame up the inclined side edges to positions on top of the frame and means 65 mounted upon the frame for effecting such movement, the latter means being shaped to engage the rollers from opposite sides for holding the same in position on top of the frame, said means being movable laterally for automatically compensating for different thicknesses of the rollers.

6. In a cleaning device, a flat, rectangular frame having downwardly inclined side edges, a cloth disposed underneath the frame, two rollers 70 having the ends of the cloth wound thereon and adapted for movement from positions alongside

opposite sides of the frame up the inclined side edges to positions on top of the frame and a pair of arms mounted upon each end of the frame so as to form an angle and having freedom of movement for increasing and decreasing the angle, the arms having fingers engaging the rolls for moving the latter up the inclined side edges when the arms are moved for decreasing the angle. 5

7. In a cleaning device, a flat, rectangular frame having downwardly inclined side edges, a 10 cloth disposed underneath the frame, two rollers having the ends of the cloth wound thereon and adapted for movement from positions alongside opposite sides of the frame up the inclined side edges to positions on top of the frame and a pair 15 of arms mounted upon each end of the frame so as to form an angle and having freedom of movement for increasing and decreasing the angle, the arms having fingers engaging the rolls for moving the latter up the inclined side edges when the 20 arms are moved for decreasing the angle, and spring actuated means for moving the arms toward each other.

8. In a cleaning device, a flat, rectangular frame having downwardly inclined side edges, a 25 cloth disposed underneath the frame, two rollers having the ends of the cloth wound thereon and adapted for movement from positions alongside opposite sides of the frame up the inclined side edges to positions on top of the frame and a pair 30 of arms mounted upon each end of the frame so as to form an angle and having freedom of movement for increasing and decreasing the angle, the arms having fingers engaging the rolls for moving the latter up the inclined side edges when 35 the arms are moved for decreasing the angle, and means for moving the arms toward each other and comprising a longitudinally movable member having arm engaging elements for spreading or contracting the same as the member moves and 40 spring means for moving the member for contracting the arms.

9. In a cleaning device, a flat, rectangular frame having downwardly inclined side edges, a 45 cloth disposed underneath the frame, two rollers having the ends of the cloth wound thereon and adapted for movement from positions alongside opposite sides of the frame up the inclined side edges to positions on top of the frame and a pair 50 of arms mounted upon each end of the frame so as to form an angle and having freedom of movement for increasing and decreasing the angle, the arms having fingers engaging the rolls for moving the latter up the inclined side edges when the arms are moved for decreasing the angle, a longitudinally movable member having arm engaging elements for spreading or contracting the same 55 as the member moves, spring means for moving the member for contracting the arms and a manually operated lever operatively connected to the member for moving the member in the opposite direction for spreading the arms whereby the rollers are released. 60

10. In a cleaning device, a flat rectangular frame having downwardly inclined side edges, a 65 cloth disposed underneath the frame, two rollers having the ends of the cloth wound thereon and adapted for movement from positions alongside opposite sides of the frame up the inclined side edges to positions on top of the frame and a pair 70 of arms mounted upon each end of the frame so as to form an angle and having freedom of movement for increasing and decreasing the angle, the arms having fingers engaging the rolls for moving the latter up the inclined side edges when the 75

arms are moved for decreasing the angle, a longitudinally movable member having arm engaging elements for spreading or contracting the same as the member moves, spring means for moving the member for contracting the arms and a manually operated lever operatively connected to the member for moving the member in the opposite

direction for spreading the arms whereby the rollers are released, the two arms being mounted to swing on a common pivot as a unit whereby they may be moved laterally as a unit to compensate for differences in the thickness of the rollers. 5

JAMES M. OBERTI.
